JOHN WILLIAM STOLLE, OF ASHLAND, MAINE, ASSIGNOR OF ONE-THIRD TO FRANK F. STOLLE, OF REDDING, CONNECTICUT.

UNBREAKABLE CANT HOOK.

1,423,781.

Specification of Letters Patent. Patented July 25, 1922.

Application filed October 10, 1921. Serial No. 506,906.

To all whom it may concern:

Be it known that I, JOHN W. STOLLE, a citizen of the United States, residing at Ashland, in the county of Aroostook and 5 State of Maine, have invented a new and useful Unbreakable Cant Hook, of which the following is a specification.

This invention relates to devices for handling logs, and is more particularly directed 10 to a new and improved cant hook.

Heretofore, in devices of this kind, the pick of the cant hook was simply driven into a handle formed of heavy seasoned maple wood and the pick readily worked 15 loose after repeated swelling and shrinking of the lower end of the stock, and the necessary hard usage to which such devices are usually subjected.

It is an object of this invention to provide 20 an indestructible cant hook, in which the handle is made of a light and cheap wood such as spruce, and is strengthened to such a degree that the strongest lumberman will be unable to break it, and in which 25 the pick cannot work loose and force its way outwardly or inwardly of the handle.

The invention will be best understood from a consideration of the following detailed description, taken in connection with 30 the accompanying drawing forming part of this specification, with the understanding, however, that the invention is not confined to any strict conformity with the showing in the drawing, but may be changed and 35 modified so long as such changes and modifications mark no material departure from the salient features of the invention as expressed in the appended claims.

In the drawing:—

40 Fig. 1 is a side elevation of the cant hook.

Fig. 2 is a longitudinal section of the same.

Fig. 3 is a view in detail of the combined reinforcing rod and pick.

45 Referring to the drawing, 1 designates the handle or stock of the hook, provided with a conical portion 2 at one end, a bore running longitudinally and centrally of the handle, and a spherical or ball-shaped end 50 3 forming a hand grip which is sheared off as shown at 4, for a purpose which will be described later.

The pick 5 formed of forged steel, comprises a conical point 6, an annular shoulder 55 7, and a conical shank 8 inserted within

the bore of the handle. Welded to the shank and forming a continuation of the same is a cylindrical metal reinforcing rod 9 extending longitudinally and centrally through the bore of the handle or stock 1. 60

Embracing the conical end of the handle is a conical metallic sleeve or socket 10 providing a reinforcing means for the end of the handle.

The shank 8 is so positioned within the 65 bore that the pick extends entirely beyond the end of the conical portion of the handle, with the shoulder 7 in abutting relation with the end of the conical sleeve and the outer end of the conical portion of the 70 handle or stock.

The outer or reduced end of the socket 10 is of the same diameter as that of the 75 base of the conical point, while the inclination of the outer surfaces of the socket and the point are identical.

The other or upper end of the reinforcing rod 9 is screw-threaded, as shown at 12, and adapted to receive the threaded portion of a spanner nut 13, which has a flat 80 section seated upon the sheared-off portion 4 of the knob or hand grip 3 of the stock 1. The outer portion of the nut is rounded in such a manner as to complete the spherical 85 shape of the knob 3. Perforations 14 are formed in the spanner nut, which nut may be turned by a suitable tool for rotating the same and drawing the rod 9 inwardly to force the shoulder 7 securely upon the ends 90 of the conical portion of the handle and the sleeve 10.

Integrally formed upon the outer surface of the reinforcing sleeve or socket 10 are a pair of ears 15, between which are pivotally mounted a hook 16, upon a bolt or pin 17. 95 The outer end of the hook is formed with a point 18 adapted to cooperate with the point 6 of the pick for gripping a log when it is attempted to move the same by means of the cant hook.

The shoulder 7 performs a triple function. First, it prevents the socket 10 from working loose; second, it prevents the pick from working deeper into the socket or coming out; and third, it offers resistance to 105 the spanner nut.

What is claimed is:—

1. In a cant hook employing a handle with a pick and a pivoted hook, a reinforcing rod passed longitudinally through the handle 11

and formed integral with the pick, said rod being held from movement longitudinally of the handle.

2. In a cant hook, the combination with a handle bored longitudinally, a reinforcing rod passed through the bore, means connected to one end of the rod to hold the same from longitudinal movement, a pick formed integral with the other end of the rod and extending beyond the handle, and a pivoted hook connected to the handle and cooperating with the pick.

3. In a cant hook, the combination with a handle bored longitudinally from end to end, a pivoted hook connected to one end of the handle, and a combined reinforcing rod and pick united as one structure, the pick extending beyond the handle while the rod fits in the bore of the handle, and means for holding the reinforcing rod and pick from longitudinal movement.

4. In a cant hook, the combination with a handle having a longitudinal bore and provided with a conical portion at one end thereof, of a reinforcing sleeve surrounding said conical portion and having ears formed integral therewith, a hook pivotally mounted between said ears, a pick comprising a conical point, an annular shoulder abutting the end of the sleeve and the end of the handle, and a shank inserted within the bore, and a reinforcing rod united to the shank and running longitudinally of the bore and having a screw-threaded end, and a nut for

engaging said end and bearing against the end of the handle.

5. In a cant hook, the combination with a handle having a longitudinal bore and provided with a sleeve at one end thereof, of a pick comprising a conical point, an annular shoulder abutting the end of the sleeve, and a shank inserted within the bore, a rod united to the shank and running longitudinally of the bore and forming a reinforcement for the handle, a nut engaging the threaded portion of the extension beyond the end of the handle, and a hook pivoted to the sleeve.

6. In a cant hook, the combination with a handle having a longitudinal bore and provided with a conical portion at one end thereof, of a sleeve surrounding said conical portion, a hook pivotally mounted to said sleeve, a pick comprising a conical point, a conical shank of less diameter than the point inserted within the bore, and an annular shoulder formed at the junction of the conical point and shank and abutting the end of the handle and sleeve, a rod united to the shank and running longitudinally of the bore and forming a reinforcement for the handle, and means for fastening the outer end of the rod and holding the same from movement.

In testimony that I claim the foregoing as my own, I have hereto affixed my signature.

JOHN WILLIAM STOLLE.
